DOUBLE OVEN INDUCTION HEATING ELECTRIC RANGE

Philip H. Peters, Jr., Greenwich, and John L. Matrone,
Schenectady, N.Y., assignors to Environment/One
Corporation, Schenectady, N.Y.

Original design application Sept. 23, 1971, Ser. No.
183,288. Divided and this application Nov. 21,
1973, Ser. No. 417,965

Term of patent 14 years

Int. Cl. D7—02

U.S. Cl. D7—118

FIG. 1

FIG. 2

FIG. 3

FIG. 1 is a perspective view as seen from the front and one side of a double oven induction heating electric range showing my new design.

FIG. 2 is a top plan view thereof.

FIG. 3 is a front elevation thereof.

This application is a division of our pending design application Ser. No. 183,288, filed Sept. 23, 1971.

We claim:

The ornamental design for a double oven induction heating electric range, as shown and described.
